UNITED STATES PATENT OFFICE.

EDMUND THOMAS, OF ERIE, PENNSYLVANIA.

FLAT-IRON HEATER.

No. 800,415.

Specification of Letters Patent.

Patented Sept. 26, 1905.

Application filed July 11, 1904. Serial No. 216,152.

To all whom it may concern:

Be it known that I, EDMUND THOMAS, a citizen of the United States, residing at Erie, in the county of Erie and State of Pennsylvania, have invented new and useful Improvements in Flat-Iron Heaters, of which the following is a specification.

This invention relates to flat-iron heaters; and it consists in certain improvements in the construction thereof, as will be hereinafter fully described, and pointed out in the claims.

The object of the invention is to provide a convenient means for heating flat-irons of different sizes and kinds, and at the same time holding the iron in a convenient position to be removed from the heater.

The invention is illustrated in the accompanying drawings as follows: Figure 1 shows a plan view of the heater. Fig. 2 shows a section on the line 2 2 in Fig. 1. Fig. 3 is a side elevation of the heater with a flat-iron having a detachable handle in place; Fig. 4, a side elevation of the heater with an ordinary iron in place.

25 A marks an inclosing casing. It is provided with slots into which the handle of the iron is placed. The enlarged part of the slot *a* is of sufficient width to engage the projections *d* of the iron *D*, having a detachable handle, (not shown,) and the bottom *a'* of the slot is arranged to engage the handle *e* of the ordinary iron *E*. The inclosing casing is preferably pyramidal shaped and has a series of supporting-slots in the sides. Arranged with- 30 in the inclosing shell is a support *B*, preferably pyramidal shaped, having flat surfaces on which the face of the iron rests. Projecting from this support *B* are the arms *b*. These are arranged between the slots. The shell *A* has the lugs *a'*, which present vertical surfaces on the inside. The arms *b* have the projections *b'* fitting these surfaces. These projections have the slots *b''*, through which the studs *c* pass. The studs *c* are screwed into the lugs *a'* and are provided with the nuts *c'*.

With flat-irons of different thicknesses it is desirable that the parts *d* on the detachable flat-iron *D* fit in the larger part of the slot *a*, and to make the space between the support *B* and shell *A* right to effect this result some adjustment is desirable. I provide this by mak-

ing the steps *b''* on the projection *b'*. By loosening the nut *c'* the support *B* may be lowered to the different steps *b''*, and thus adjusted to any height desired. It will be apparent that by raising or lowering it the space between the shell and support *B* is diminished or increased by reason of the tapered shape of the support and shell.

What I claim as new is—

1. In a flat-iron heater, the combination of an inclosing shell having slots therein the edges of which form supports for an iron and a support within the shell, said shell and support being arranged to hold the iron in an upright position with the handle portion exposed; and means for adjusting the support relatively to the shell to accommodate different thicknesses of irons.

2. In a flat-iron heater, the combination of the pyramidal-shaped inclosing shell having slots therein for the reception of the flat-iron handles; a support arranged within the shell; and means for adjusting the support vertically to vary the space between the support and the shell for different thicknesses of irons.

3. In a flat-iron heater, the combination of the inclosing shell having slots for the reception of the iron handles, the support *B* arranged in the shell opposite the slots, said support having projections *b'*, in the ends of which are slots *b''* and on which are steps *b''* for permitting the adjustment of the support.

4. In a flat-iron heater, the combination of the shell having the slots *a* with the extensions *a'* narrower than the main portions of the slots *a*, and the lugs *2* thereon; the support *B* arranged within the shell and having flat surfaces opposite said slots, and arms *b* extending from said support *B*; said arms *b* having projections *b'* provided with steps *b''* and with slots *b''*; and the screws *c* extending through said last-named slots for attaching the support to the shell.

In testimony whereof I have hereunto set my hand in the presence of two subscribing witnesses.

EDMUND THOMAS.
